VARIABLE COMPRESSION RATIO INTERNAL COMBUSTION ENGINE

Kenjiro Tsuneda, Kyoto, Japan

Application September 1, 1936, Serial No. 98,965
In Japan November 18, 1935

3 Claims. (Cl. 123—48)

This invention relates to an internal combustion engine which is provided with means for varying the compression ratio for obtaining high thermal efficiency under varying conditions.

5 In internal combustion engines of the Otto cycle type, the compression ratio is limited within a safety range so as to prevent advanced ignition or detonation even when operating under over load, or when operating with the richest 10 mixture and at a considerably heated condition. Therefore, it is not possible under full load to obtain allowable maximum compression ratio. Under a lighter load, it is desirable that a higher 15 compression ratio be obtained, in view of the decrease of the amount of suction or dilution of the mixture. However, in an old engine with a fixed volume of combustion chamber, it has been unavoidable that under lighter load the compression ratio greatly decreases below the maximum 20 compression ratio allowed by the mixture then drawn in, whereby the thermal efficiency of the engine is considerably lowered.

An object of the invention is to provide the internal combustion engine with means by which 25 the compression ratio can be conveniently varied according to the load of the engine, number of revolutions, nature of the fuel, etc., so as to always obtain maximum thermal efficiency under varying conditions.

30 With the above-mentioned object in view, according to this invention, a movable member is incorporated in the wall of the combustion chamber, which movable member is adapted to be actuated by a mechanical means and moved from 35 or toward the working piston, whereby the compression ratio can be readily varied, so as to always obtain maximum compression ratio under varying conditions. By such means, it is possible to obtain increased thermal efficiency under varying loads, and especially advantageous results 40 can be obtained when operating under lighter load.

According to this invention, the means for varying the compression ratio may be arranged on 45 the cylinder head, quite independently of the main part of the engine, so that the operation of the main parts is by no means affected. Any existing engine may be equipped with the compression ratio varying mechanism according to 50 this invention, by a simple operation, without necessitating any substantial change in the construction of the main parts of the engine.

The invention will now be fully described with 55 reference to the embodiment shown in the accompanying drawing, in which:

Figure 1 is a longitudinal section of a portion of an internal combustion engine according to this invention; and

Figure 2 is a plan thereof partly in section.

Referring to the drawing, the reference numeral 1 designates a cylinder, 2 a cylinder head, and 3 the main piston. The cylinder head 2 is provided with a cavity 4 opposite to the piston 3, and in this cavity 4 there is slidably mounted a piston-like movable member 5. Said movable member 5 has a central rod 7 extending upwardly and formed with a screw-thread 6. Between the upper wall 8 of the cavity 4 and a top plate 9 there is arranged a pinion 10 having its axial bore internally screw-threaded and engaging with said threaded rod 7. Engaged with said pinion 10 is a toothed rack 11, which is adapted to be moved horizontally on the cylinder head.

The toothed rack 11 may be actuated by any manually or automatically controlled means. For 20 automatic control, means may be provided which is responsive to variation of pressure or temperature of explosion gas, or suction pressure in the inlet manifold, according to variations of the load of the engine and other varying conditions. 25 In the embodiment shown, means responsive to variation of explosion gas pressure is provided for actuating the rack 11. A pipe 16 which is in communication with the combustion chamber of the engine, is connected to the inlet side of the 30 valve chest containing a double-seated valve 12. Said valve 12 acts as an inlet and outlet controlling valve, and is opened by the ingress of the explosion gas, the latter being introduced into a servo-motor cylinder 13, acts upon a servo-motor 35 piston 14. A rod 15 of said piston 14, is connected to the toothed rack 11.

When the pinion 10 is rotated in either direction by the toothed rack 11, the threaded rod 7 is raised or lowered, and the position of the movable member 5 is varied accordingly. Thus, the effective volume of the combustion chamber is varied for the purpose of obtaining the desired compression ratio. When the automatic controlling mechanism as mentioned above with reference to 45 Figure 2 is employed, according to the reduction of the load and consequently according to the decrease of the maximum explosion gas pressure, the valve 12 is maintained in closed position by the action of a spring 17, and the gas in the servo-motor cylinder is discharged through a discharge pipe 19 by the action of a spring 18 acting upon the piston 14. Together with the piston rod 15, the toothed rod 11 is moved in such a direction that the movable member 5 is lowered, thereby 50

automatically increasing the compression ratio. Upon increase of the load, increased explosion gas pressure will open the inlet side of the valve 12, closing the outlet side thereof at the same time, 5 and increasing the pressure within the servo-motor cylinder, whereby the rack 11 and the associated mechanism are actuated in the reverse direction, so that the movable member 5 is lifted. Thus, the compression ratio is automatically 10 decreased.

During the operation of the engine, the movable member 5 is subjected to high temperature, and due to the fact that it is moved intermittently and irregularly for a short stroke, it is liable to be 15 subjected to undue expansion causing a tight fit in the cavity 4, which will prevent the easy movement of the member 5 for varying the compression ratio. In order to remove such a disadvantage, the movable member 5 is preferably made hollow, 20 and the rod 7 is provided with a canal 20 within which is a water tube 21, which has an outer diameter smaller than the inner diameter of the canal 20, thus leaving an annular passage around the tube 21. The lower end of the water tube 21, 25 is in communication with the hollow chamber within the member 5, and at the upper end it is connected to a water feed pipe 22. A water pipe 23 is connected to the canal 20. By such means cooling water is continuously fed into the movable 30 member 5, for cooling the same. This will also prevent the lubricant from splitting up, due to being heated to a high temperature.

In the drawing a packing 24, is fitted at the 35 sliding portion of the movable member 5, and a piston ring 25, is fitted to said piston-like movable member. 26 is a bearing. 27 is a key for guiding the movement of the rod 7. 28 is a spring for preventing vibrating movement of the member 5.

What I claim is:

40 1. A variable compression ratio internal combustion engine comprising a cylinder, a main piston in said cylinder, a cylinder head having a cavity and forming a combustion chamber together with said cylinder and the main piston, a piston-like movable member slidably mounted in said cavity in the cylinder head, a threaded central rod fixed to said piston-like movable member, a pinion having its bore internally screw-threaded and engaging with said threaded central rod, a 45 toothed rack engaging with said pinion and adapted to be moved horizontally on the cylinder head, a servo-motor cylinder, a servo-motor piston in said servo-motor cylinder and connected to said toothed rack, a pipe connecting said servo-motor cylinder to said combustion chamber, a controlling valve in said pipe for controlling the flow of explosion gas from said combustion chamber into said servo-motor cylinder.

in said servo-motor cylinder and connected to said toothed rack, a pipe connecting said servo-motor cylinder to said combustion chamber, a controlling valve in said pipe for controlling the flow of explosion gas from said combustion chamber into said servo-motor cylinder.

2. A variable compression ratio internal combustion engine comprising a cylinder, a main piston in said cylinder, a cylinder head having a cavity and forming a combustion chamber together with said cylinder and the main piston, a piston-like movable member slidably mounted in said cavity in the cylinder head, a threaded central rod fixed to said piston-like movable member, a pinion having its bore internally screw-threaded and engaging with said threaded central rod, a toothed rack engaging with said pinion and adapted to be moved horizontally on the cylinder head, a servo-motor cylinder, a servo-motor piston in said servo-motor cylinder and connected to 10 said toothed rack, a pipe connecting said servo-motor cylinder to said combustion chamber, a double-seated valve acting as an inlet and outlet controlling valve and controlling on one hand the flow of explosion gas from said combustion chamber to said servo-motor cylinder, and on the other hand controlling the flow of gas from said servo-motor cylinder.

3. A variable compression ratio internal combustion engine comprising a cylinder, a main piston in said cylinder, a cylinder head having a cavity and forming a combustion chamber together with said cylinder and the main piston, a hollow piston-like movable member slidably mounted in said cavity in the cylinder head, a 20 threaded central hollow rod fixed to said piston-like movable member and having its bore formed as a water canal which is in communication with a hollow chamber in said piston-like movable member, a pinion having its bore internally screw-threaded and engaging with said threaded central rod, a toothed rack engaging with said pinion and adapted to be moved horizontally on the cylinder head, a servo-motor cylinder, a servo-motor piston in said servo-motor cylinder and connected to 25 said toothed rack, a pipe connecting said servo-motor cylinder to said combustion chamber, a controlling valve in said pipe for controlling the flow of explosion gas from said combustion chamber into the said servo-motor cylinder.
